UNITED STATES PATENT OFFICE.

AARON W. PRATT, OF PULTNEYVILLE, NEW YORK

IMPROVEMENT IN FENCES.

Specification forming part of Letters Patent No. 63,296, dated March 26, 1867.

To all whom it may concern:

Be it known that I, AARON W. PRATT, of Pultneyville, Wayne county, New York, have invented certain new and useful Improvements in the Construction of Fences; and I hereby declare that the following is a full, true, and exact description of the same, reference being had to the accompanying drawings, and to the letters of reference marked thereon:

Figure I in the annexed drawings, which are made a part of this specification, represents a side elevation of a section of my fence.

The letter A designates the main posts of the fence. The wire c, that is designed to hold the paling in position, is first doubled and then passed through a hole in one of the posts A, and keyed on the outer side of the post with an iron pin. A pale, b, is now placed at the proper distance from the post A, and a strand of wire made to pass over each of the opposite sides of the first pale. The strands c are then bent so as to cross each in manner resembling the letter X, and when thus bent another pale is inserted. This operation is repeated until all the pales intended to complete one panel are embraced near the top by the two strands of wire. Another wire is now inserted near the bottom of post A for the purpose of confining the lower ends of the pales. The lower wire is passed through the post A and bent to hold the pales in the manner described above. When the pales b are all in position the ends of both strands of wire c are passed

through a hole in the opposite post A, and then bent back so as to completely embrace the post A. The ends of the wire are now twisted around the strands so as to form a shoulder inside of post A. After the strands are thus secured, the cap D is dovetailed into the top of posts A. This arrangement gives greater strength and stability to the fence, and at the same time adds much to its finished appearance.

I am aware that a fence has been constructed somewhat similar to mine, the pales being diamond-shaped in place of being flat at the inner and outer sides. But, in order to give that fence a uniform and handsome appearance, the pales have to be manufactured by machinery, thus adding greatly to its cost; whereas mine can be made out of inch boards by any one who knows how to use a hand-saw, and can mortise the posts in the sill E.

Having thus described my invention, what I claim, and desire to secure by Letters Patent, is—

The sill E, the posts A, the cap D, the pales b, and the wire strands c, the whole arranged, constructed, and operating substantially as herein described.

In testimony that I claim the foregoing as my own, I hereby affix my signature in presence of two witnesses.

AARON W. PRATT.
